To all whom it may concern:

Be it known that I, Igor I. Sikorsky, a citizen
of the United States, residing at Nichols, in the
county of Fairfield and State of Connecticut, have
invented a new, original, and ornamental Design
for an Airplane, of which the following is a speci-
fication, reference being had to the accompanying
drawing, forming part thereof.

Figure 1 is a top view of my design,
Figure 2 is a front elevation thereof,
Figure 3 is a side elevation.

I claim:

The ornamental design for an airplane, as
shown.

IGOR I. SIKORSKY.
